(57) **CLAIM**

The ornamental design for a display screen with a graphical user interface for fuel valve diagnosis, as shown and described.

DESCRIPTION

The file of this patent contains at least one drawing/photograph executed in color. Copies of this patent with color drawing(s)/photograph(s) will be provided by the Office upon request and payment of the necessary fee.

1. Display screen with graphical user interface for fuel valve diagnosis

1.1 is a front view of a display screen with graphical user interface for fuel valve diagnosis; and

1.2 is a supplemental view of 1.1, but shown without all disclaimed portions of the graphical user interface, for the purpose of more clearly illustrating the claimed design.

The blue-colored portions of 1.1 illustrate portions of the graphical user interface that form no part of the claimed design. All text, characters, and numbers in 1.1 illustrate portions of the graphical user interface that form no part of the claimed design. The outermost broken line rectangle in 1.1 and 1.2 illustrate the display screen that forms no part of

(Continued)

the claimed design. The remaining broken lines in 1.1 illustrate portions of the graphical user interface that form no part of the claimed design.
